UNITED STATES PATENT OFFICE.

EDWARD S. RAFF, OF CANTON, OHIO.

CHECK RATING AND PUNCHING MACHINE.

SPECIFICATION forming part of Letters Patent No. 433,541, dated August 5, 1890.

Application filed January 2, 1890. Serial No. 335,678. (No model.)

To all whom it may concern:

Be it known that I, EDWARD S. RAFF, a citizen of the United States, and a resident of Canton, county of Stark, and State of Ohio, have invented a new and useful Improvement 5 in Check Rating and Punching Machines, of which the following is a full, clear, and exact description, reference being had to the accompanying drawings, making part of this specification.

My invention relates to improvements in machines for perforating and printing figures on bank-checks or other papers to correspond with the amount or value otherwise indicated 15 on such check or paper to prevent subsequent alteration.

With these ends in view my invention consists of certain features of construction, and combination of parts, as will be hereinafter 20 described, and set forth in the claims.

In the accompanying drawings, Figure 1 is a perspective illustrating my invention. Fig. 2 is a similar view of the bottom plate, die-plate, and bank of keys. Fig. 3 is a similar 25 view of a comb or guide-plate; Fig. 4, a similar view of the frame, showing the guide-plate, paper-holder, and sliding guide; Fig. 5, a similar view of the sliding guide; Fig. 6, a plan view of the keys and middle portion of the 30 frame; Fig. 7, an end elevation of the supporting-frame and keys; Fig. 8, a perspective comprising the perforating and printing 35 punch and die; Fig. 9, a plan view of a key-blank. Fig. 10 is an enlarged view of a portion of one of the points that outline the type-character.

The supporting-frame consists of two portions and may be made of any suitable cast metal, and of the form, or substantially so, as 40 that shown in Figs. 1 and 4, the bottom portion A having a wide table portion B. To the frame A is secured overhung end frame-pieces C against movement by screw-bolts a, as shown in Fig. 7, said end frames having upwardly-projected portions a¹, at the upper 45 end portions of which there is provided an aperture a², in which is placed a bar D, connecting the said portions and forming a support and slide for the key-frame E. On the 50 front end of the frame-pieces C is secured a plate F, thus completing the frame of the ma-

chine and providing other features herein-after explained.

The key-frame E is composed of the rearwardly-descending side bars a², which are secured together at their upper front ends by the comb-plate G and at their lower rear end portions by the comb-plate H. At the upper end portions of the side bars a² there is provided apertures a³, through which the bar D 55 is passed and upon which the key-frame may slide. The bottom plate J is secured at its rear portion to the rear portion of the key-frame E, the front edge to slide upon a ledge a⁴, formed on the rear portion of the table B, 60 as shown in Fig. 7, the top of the plate to be on a line with said table. The rear portion of the key-frame is supported on a ledge formed on the front side of the rear portion of the frame A, the roller a⁵ resting against the vertical portion and projecting over the top, as 65 shown, and, if preferred, the said portion of the said frame may be supported on the flanged portion of said roller resting on the top of the frame A, as shown. As shown in this case, 70 the plate J is provided with an oblong aperture a⁷ at its front portion, over which is placed the die-plate a⁸; but, if preferred, the dies may be formed in the plate J, the said dies 75 to consist of a series of small perforations 80 outlining the numerals or characters, as shown at b⁶, Fig. 8.

The type-keys L are cut from sheet metal, a blank shown in Fig. 9, the upper end portion to be twisted one-fourth of a turn to form 85 a finger portion d³, as shown in Figs. 1, 6, and 7, the lower end portion b having a perforation, as b', the arm portion b² turned over to one side and back on itself, as shown in Figs. 1, 6, and 8, the lower face b³ to be provided with a raised type-surface or a type 90 sunk into face portion b³, with either of the above-mentioned forms, as type-characters may be printed without the use of a die or any form other than the paper resting on the 95 plate J; but, if desired, die may be formed in said plate to correspond with the raised type, by which the paper may be perforated, said perforations to correspond in character 100 with the type; but preferably, and for the purpose of this case, I have constructed a character-type, as shown in Fig. 8, consisting of a

series of steel pins, as b^5 , set in the type-face portion b^3 to outline the characters, said pins having a short sharpened conical end portion provided with longitudinal ink channels or 5 grooves b^x . The die for said type, constructed as shown at b^6 , Fig. 8, consists of a series of small perforations, as b^4 , to outline the characters to correspond with the type-pins, and in operation a paper is placed over 10 the die, the type brought down, the point of the pins to puncture the paper, the body of the pin to press the paper into the perforation, thus indenting and puncturing the paper, as will be hereinafter explained. However, if a character formed of small perforations is preferred, the end of the pins b^5 may 15 be so formed as to cut out the paper by entering the perforations b^4 of the die b^6 , and thereby leaving a similar perforation in the 20 paper.

Numerals or characters are placed on the finger portion a^3 of the keys to correspond with the type on the same key. The keys so formed are placed on the rod b^7 and spaced 25 apart by the comb-plate H, said plate having a series of elongated slots b^8 , in which the rear end portion of the keys L are placed, as shown in Figs. 1 and 2.

In Figs. 2 and 6 a coil-spring b^9 is shown 30 placed about the rod b^7 , between the keys. The energy of the spring is exerted to hold the front end portion of the key up in the slot b^9 in the comb-plate G.

In Fig. 7 I have shown another form of 35 spring, (indicated as d), which is made of plate metal, the body portion of which is secured to the bottom plate J, the front end turned up to take under the key, as shown in Fig. 2. The front end portion of the key L 40 is secured against lateral movement by the comb-plates G, and the lug b^{10} into the slot d^2 in the plate M to guide the pins or punches b^5 of the type b^3 into the perforation b^4 in the die b^6 . For the purpose of this case I have 45 shown the two comb-plates G and M, both of which are secured at their upper end portions to the side bars of the key-frame, as shown, and are projected downwardly; but, if preferred, the comb portion of the plate G may 50 be dispensed with and the slots d^2 in plate M extended up to the flanged portion of the plate the full height of the vertical movement of the key. The bank of keys constructed as hereinbefore stated are now placed in the 55 frame A, the plate J resting on the ledges, as stated, and the bar D passed through the perforation a' in the upwardly-projected portion of the frame-pieces C and through the perforations a^3 in the side bars a^2 of the key-frame 60 E, thus forming a support and slide for the bank of keys, as shown in the drawings, which may be moved thereon from one end of the frame to the other.

In the plate F is provided a series of vertical slots d^5 to guide the key and type to the desired point on the paper, and to provide for the desired spacing between characters and

against mistakes a sliding guide Q is provided, as shown in Figs. 1, 4, and 5, the latter showing the reverse side, said slide made 70 of sheet metal, and is formed substantially as shown in the drawings, having two side portions d^6 and d^7 to embrace and slide upon the front plate F, the side d^7 having a V-shaped notch R, having one side d^8 graded so as to 75 move the slide the distance of one space to bring the small V-notch S in side d^6 of the slide over the next slot d^5 to the right. There is also provided on the front side of the slide a thumb-piece d^9 , and on the plate F a corresponding piece d^{10} .

To hold the check or other paper in position to be indented and printed, a spring-actuating presser-foot N is provided, as shown in Fig. 1, having a foot portion provided with 85 toes h^3 to hold the paper from sliding or turning on the table, the spring h^3 exerted against the back portion of the lever h^4 .

To ink the type or the puncturing-pins, ink-rollers, as T, are provided, as shown, supported on and rotated about pins h^5 , secured in the notched guide-plate F, the roller being supplied with ink in the usual way. As the keys are moved back and forth in their normal position, the type or pins hereinbefore 95 described will engage said rolls and rotate them about the supporting-pins, and in so doing will receive on the said type or points the desired amount of ink.

In operation the thumb and finger is placed 100 on the thumb-pieces d^9 and d^{10} , the slide Q, drawn against the foot-lever h^4 , by which the foot is raised, the check placed on the table B under the foot, as shown in Fig. 1, the slide released, the spring will move the slide to the 105 right, the "V," S resting over the left-hand slot d^5 in the plate F, the first key having the dollar-character is brought down, the shoulder h striking the graded side of the V-notch R on the long side at x and moved along and 110 down on said grade to 2, by which movement the slide will be moved to the right one space, bringing the V-notch S over the second slot d^5 , and the type in contact with the paper to 115 indent, puncture, and print the dollar-character. The keys will then be moved to the left, bringing the key having the character 3 over the V-notch S, and the key brought down as before stated, to print the character 3. The keys are then moved farther on to the 120 left, bringing the key 7 over the V-notch S, the operation of printing repeated. The keys are then moved to the right, bringing key 5 over the said V-notch, and the operation of printing repeated. The keys are then moved to the 125 left to bring the character 0 over the notch S, when the operation of indenting, puncturing, and printing are repeated, marking the said check \$3,750. By providing the points that 130 outline the characters with grooves or channels the ink supplied thereto by the rollers will be carried through the check when punched, and when the points are withdrawn the edge or wall of the puncture will scrape

the ink from the channels or groove, thus printing the check upon each side.

Having thus fully described the nature and object of my invention, what I claim as new, and desire to secure by Letters Patent, is—

- 5 1. In a check-rating machine, a type-key L, having a finger d^3 , a type-supporting arm b^2 , guide b^{10} , and a type or punch, a shoulder h , and a downwardly and rearwardly projected portion having a perforation b' , by which the key is pivotally secured to the key-frame, substantially as described, and for the purpose set forth.
- 10 2. In a check-rating machine, the combination, with the type-keys L and the plate F, having the spacing-slots d^6 , of the sliding guide Q, substantially as described, and for the purpose set forth.
- 15 3. In a check-rating machine, the combination, with a character-type consisting of pointed pins arranged to outline a character and provided with ink-channels, of a die-plate having perforations to correspond with the pins, and a roller to ink said pins, substantially as set forth.
- 20 4. In combination with the supporting-frame, as hereinbefore described, of the type-key, type, and corresponding dies, spacing-slots d^5 , slide Q, and presser-foot N, substantially as described, and for the purpose set forth.
- 25
- 30

5. The combination, with the type-keys and the slotted spacing-plate, of the automatically-sliding guide, whereby when one of the keys is depressed to register with one slot in said plate the guide is moved to the adjacent slot, substantially as set forth. 35

6. The combination, with the supporting-frame provided with a fixed table, of a bank of punches supported to slide above said table, a notched guide-plate, a sliding guide engaged therewith, and a check-holder located in the path of the sliding guide, whereby when it is desired to reset the sliding guide for another check its movement will trip the check-holder and release the punched check, 40 substantially as set forth. 45

7. In a check-rating machine, the combination, with a character-type consisting of pointed pins arranged to outline a character and having grooves in their sides, of a die-plate having perforations to correspond with the pins, and a roller to ink said pins, substantially as set forth. 50

In testimony whereof I have hereunto set my hand this 28th day of December, A. D. 55 1889.

EDWARD S. RAFF.
